UNITED STATES PATENT OFFICE.

AUGUST SCHWICKERT, WILHELM SCHWICKERT, AND EDUARD SCHWICKERT, OF HÖCHST-ON-THE-MAIN, GERMANY.

SPRING-PROPELLED CARRIAGE.

SPECIFICATION forming part of Letters Patent No. 322,071, dated July 14, 1885.

Application filed September 30, 1884. (No model.)

To all whom it may concern:

Be it known that we, AUGUST SCHWICKERT, WILHELM SCHWICKERT, and EDUARD SCHWICKERT, all three subjects of the Empire of Germany, residing in Höchst-on-the-Main, Germany, have invented certain new and useful Improvements in Spring-Propelled Carriages, of which the following is a specification.

10 Our invention relates to improvements in carriages or vehicles driven by a spring-motor; and it has for its object to propel the carriage by two spiral springs wound of flat steel in the well-known conical shape of the buffer-springs, which driving-springs may by compression be set in tension either simultaneously or alternatively. We attain this object by the mechanism illustrated in the accompanying drawings, in which—

15 Figure 1 is a vertical longitudinal section, and Fig. 2 a horizontal section, of the entire carriage. Figs. 3 and 4 are vertical transverse sections of the carriage, and Figs. 5 to 11 detail views of the driving mechanism.

20 The carriage, which is carried by a small leading and steering wheel, g , and two driving-wheels, $A A$, at the rear part of the carriage, is driven by two strong horizontally-placed spiral springs, a , of flat steel wound in the 25 conical shape of the buffer-springs. These springs are compressed and brought in tension, and then their straight movement during the extension is converted into the rotatory motion of the two driving-wheels. For 30 this purpose, to one extremity of the springs a , the other larger base of which is secured to the head-wall of the carriage-frame, is attached the rack C , supported by the friction-roller c , and gearing with pinion d . The rotation of 35 the pinion d is transmitted to the driving-wheels by the toothed gear $d' d'' d''' d''''$. The toothed wheels d and d' are keyed upon a common shaft, B , the toothed wheels d'' and d''' are placed upon another common shaft, C , and the 40 toothed wheel d'''' is secured upon the axle D of the driving-wheels A . The springs a are compressed by means of the toothed gear $e e' e'' e''' d$. The shaft 3 of the uppermost pinion, e , has square extremities, to which hand wheels or 45 cranks for compressing or bending the springs are applied. The cog-wheel e' , gearing with

pinion e , is fastened upon a common shaft, 5 , with two pinions, e^2 . Each of the pinions e^2 is, as shown clearly by Figs. 5, 6, and 7, provided with a central socket, f . The forked lever m enters an annular recess of this socket f , and as each pinion is sliding by key and key-groove longitudinally on the shaft 5 , the forked lever m serves for bringing the pinions e^2 in and out of gear with the cog-wheel e^3 . The two cog-wheels e^3 , one of which is disposed for each pinion e^2 , are loose upon their common shaft 8 , and gear each with one of the two pinions d , gearing with the racks $b b$. In this way, by turning the shaft 3 of pinion e , and bringing one or the other pinion e^2 in gear with the corresponding cog-wheel e^3 , one or the other of the springs a , or also the two springs, at the same time may be compressed. Now, for retaining, first, the springs a , when entirely compressed; secondly, for bringing in action the springs a when desired; thirdly, for coupling the shaft-bearing cog-wheel d' only with that pinion d which is still driven by a spring, a ; fourthly, for uncoupling again automatically the pinion d from the cog-wheel d' as soon as the spring a has lost its tension, the mechanism (shown more detailed by Figs. 8 to 11) is employed. Both pinions d are loose upon their common shaft B , which, as already stated, carries also the cog-wheel d' . Each pinion d is provided with a central socket, z , having several grooves z' , into which the corresponding keys, p , of the coupling-sleeve p , sliding by groove and key longitudinally upon the shaft B of pinion d , may enter. The two coupling parts p and z may also be provided with clutches instead of the keys and grooves, or have any other of the usual coupling arrangements. The spiral wire 50 spring q , surrounding the socket z , presses against the coupling-sleeve p . At the side of the parts $d z p$ and parallel to their axis is arranged a flat slider, n , prevented from turning and provided with a square hole, o . This hole is destined to let pass the rack b . As soon as by turning the lever r the slider n , maintained in position by spiral spring v , is moved aside, the hole o will come in face of the rack b , and the latter, propelled by the 55 spring a , will pass through n and transmit its movement to the gearing-pinion d . The

turning of lever r is effected by turning the screw u , the nut t of which is connected by the links ss to the end of lever r . A small catch, w , hinged to the extremity of the slider 5 n , is maintained usually under the action of the depressing-spring x in the position shown by Fig. 10. Consequently it will catch, when the slider n is moved laterally, the coupling-sleeve p and push the same over the socket z , whereby 10 the rotation of pinion d is transmitted to the cog-wheel d' . In this way, by turning the screw u , the spring a , disposed at the corresponding side of the carriage, is given free, and propels by its tension the driving-wheels. 15 As soon as the spring a has stretched entirely and lost all its tension, the arm y , Figs. 2 and 11, attached to the inner extremity of rack b , will push against the catch w and turn the same aside, so that the coupling-sleeve p becomes 20 free and is raised and uncoupled from z by action of spring q . Catch w will then bear on the cylindrical surface of the coupling-sleeve p . Now, as pinion d is again loose on its shaft, the spring a at the respective side of 25 the carriage, may again be compressed, while the second spring, a , at the other side of the carriage, continues to act upon the driving-wheels. As soon as the spring a is entirely 30 compressed, the lever r is turned back by means of the screw u , so that the slider n , raised by spring v , follows this movement and stops by its solid body the rack b . When the 35 catch w comes over the edge of sleeve p , it takes by action of spring x again the position shown by Fig. 10, in which it catches the sleeve p . By turning the lever r the parts p and z will be again coupled. The steering-wheel g is mounted in the fork g' , which is

turned round its axis by moving the lever k , guided in the slide l , and connected with fork 40 g' by lever h and connecting-rod i , Figs. 1 to 4. For stopping the carriage one of the usual brakes may be employed.

We claim as our invention—

1. In a spring-propelled carriage, the combination of one or more conical spiral springs, wound of flat steel in the shape of the buffer-springs and united with the rack b , with the pinion d , which transmits by a gearing the movement produced by the compressed springs 45 a to the driving-wheels of the carriage, as described.

2. The combination of the coupling-sleeve p , with coupling-socket z , of pinion d , spring q , slider n , with hole o , spring v , catch w , 50 spring x , and the arm y , attached to rack b , as and for the purposes specified.

3. The combination of lever r , links ss , nut z , and screw u , as described, and for the purpose 55 set forth.

4. The combination of the gearing toothed wheels e e' e'' with the gearing-pinions e^2 e^2 , sliding on their common shaft and provided with central sockets, f , with annular recesses into which enter the forked levers m , as described, and for the purpose set forth. 60

In witness whereof we have hereunto signed our names in the presence of two subscribing witnesses.
